Primary Examiner—James Gandy*Assistant Examiner*—Stacia Sinuik*Attorney, Agent, or Firm*—Longacre & White[57] **CLAIM**

The ornamental design for a front face of a vehicle wheel, as shown and described.

DESCRIPTION

FIG. 1 is a front elevational view of the front face of a vehicle wheel according to the present invention; and, FIG. 2 is a perspective view of the front face of a vehicle wheel as shown in FIG. 1;

The broken line showing of environment is for illustrative purposes only and forms no part of the claimed design.
